Primary Examiner — Katherine Glennon(74) *Attorney, Agent, or Firm* — Saidman DesignLaw Group, LLC(57) **CLAIM**

The ornamental design for a wristwatch, as shown and described.

DESCRIPTION

FIG. 1 is a perspective view of a first embodiment of a wristwatch showing our new design;

FIG. 2 is an enlarged detail thereof, as defined by the dashed rectangle 2 in FIG. 1;

FIG. 3 is a front view of FIG. 1;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of a second embodiment of a wristwatch showing our new design;

FIG. 10 is an enlarged detail thereof, as defined by the dashed rectangle 10 in FIG. 9;

FIG. 11 is a front view of FIG. 9;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The drawings include surface shading which illustrates contour and not surface ornamentation.

The oblique shade lines illustrate a transparent surface.
